[57] CLAIM

The ornamental design for a combined electric cord reel and dispenser, as shown and described.

DESCRIPTION

FIG. 1 is a perspective view of a combined electric cord reel and dispenser showing my new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top plan view thereof; and,

FIG. 7 is a bottom plan view thereof.

The electric cord shown in FIGS. 2 through 7 is shown in broken lines to indicate that it is included as environment to the claimed design and forms no part of the claimed invention.

FIG. 1

FIG. 2
